UNITED STATES PATENT OFFICE.

MORRIS ABRAMOVITZ, OF BALTIMORE, MARYLAND, ASSIGNOR TO DAVID B. LEVY, OF NEW YORK, N. Y., A CORPORATION OF NEW YORK.

SYRINGE.

1,267,616.

Specification of Letters Patent. Patented May 28, 1918.

Application filed December 1, 1916. Serial No. 134,429.

To all whom it may concern:

Be it known that I, MORRIS ABRAMOVITZ, a citizen of the United States, residing at Baltimore, State of Maryland, have invented 5 certain new and useful Improvements in Syringes, of which the following is a specification.

The present invention relates to improvements in syringes and has for its object to 10 provide a syringe which is particularly adapted for injecting drugs into and treating the posterior urethra. The urethral canal being normally curved at its posterior part and having between the anterior and 15 posterior parts a muscle, the compressor urethra muscle, which surrounds and keeps it compressed, makes it practically impossible to inject drugs into the posterior urethra by means heretofore provided except by introducing a catheter or a curved metal instrument through which drugs may be injected. The condition requiring injection of 20 drugs into the posterior urethra is always inflammatory and therefore the introduction 25 of a catheter or steel instrument is irritating and tends to create new areas of inflammation. By the present invention the necessity for employing such devices as catheters or similar instruments in the treatment of 30 such diseases is avoided.

In the accompanying drawing,

Figure 1 is an elevation of a syringe constructed in accordance with the present invention, showing the barrel empty and the 35 air bulbs in the position occupied just prior to a liquid charge being drawn into the barrel;

Fig. 2 is a sectional view showing the liquid in the barrel;

Fig. 3 is a similar view showing the position of the parts immediately after the liquid has been expelled from the barrel, and

Fig. 4 is a similar view showing the air pressure means fully compressed.

Referring to the drawing it will be seen 45 that the syringe comprises a barrel 1 which may be of any suitable form and material. As shown, such barrel is made of glass having a tapered section 2 at one end through 50 which is formed the inlet and discharge opening 3. Toward its other end the barrel 1 is enlarged in diameter and the walls of the opening at the end opposite the outlet 3 are flared outwardly to provide a seat in which is fitted the neck-like portion 5 of a

compressible air bulb 4. Preferably as shown the barrel 1 is provided with suitable graduations, the embodiment of the invention illustrated being designed to receive liquid to the maximum amount of 15 c. c. 60

The bulb 4 is made of rubber or other suitable material and the neck section 5 thereof is preferably made relatively thick and provided with a centrally arranged duct or passage 6. By this construction entrance 65 of liquid into the bulb 4 is prevented and the contents of the barrel 1 may be discharged, regardless of the position in which the instrument is held.

A second air bulb 7 is superposed on the 70 bulb 4 with which it communicates through an opening 8. The walls of the inner bulb or the one directly seated on the barrel are, as shown, thicker and the size or capacity of such bulb greater than the outer bulb 7. 75 For example, the outer bulb has a capacity of 10 c. c. while the inner or lower bulb is of twice that size or adapted to receive 20 c. c. Owing to the difference in thickness of the walls of the two bulbs, the outer one 80 may, as shown in Figs. 1 and 3, be compressed independently of or without affecting the normal condition of the walls of the inner, larger, bulb. The amount of air displaced by compressing the outer bulb 7 is 85 sufficient to cause a suitable quantity of liquid to be drawn into the barrel 1 as said outer bulb is allowed to expand or return to its normal condition, as is shown by comparison of Figs. 1 and 2. Therefore when 90 it is desired to discharge the contents of the barrel 1 it is only necessary to again compress the outer bulb, as shown in Fig. 3. The parts are so proportioned that compression of the outer bulb, after the desired 95 amount of liquid has been drawn into the barrel 1 and the latter inserted in the urethral opening, will act to force all of the liquid from the barrel and into the anterior 100 urethra. Preferably the capacity of the upper or outer bulb will be approximately that of the anterior urethra, say 10 c. c.

The pressure exerted by the outer bulb is not sufficient to force the liquid beyond the section of the urethral canal compressed by 105 the compressor urethral muscle, but by a simultaneous relaxing of such muscle and compression of the larger, inner bulb 4 (as shown in Fig. 4) the liquid will be readily forced into the posterior part of the urethral 110

canal. The liquid will be retained in the posterior urethra owing to the shape thereof, while the excess of air will pass over into the bladder.

5. It will be seen that by the present invention, employing two air bulbs, the smaller, outer one of which is independently compressible, it is possible to readily draw into barrel 1 exactly the amount of liquid 10 desired, which cannot be done by merely partially compressing a single bulb, and further the two volumes of air may be accurately proportioned so that while the first will only cause the liquid to enter the anterior canal compression of the inner, larger, bulb will insure the forcing of such liquid 15 into the posterior canal. Again, by the present invention the amount of liquid drawn into the barrel need never come into contact with the bulbs. This is important as the effect 20 of sterilizing the rubber from which the bulbs are formed acts to separate small particles which collect in the interior of the bulb and if the liquid were to come in contact 25 therewith it might be deleteriously affected.

The improved syringe is superior to those in which a piston or means other than air pressure is employed for expelling liquid 30 from the barrel, as it insures that the entire liquid contents will be expelled and there will be no wasting thereof. The operation of the device is very simple and may be used for the purpose stated without requiring the 35 service of a trained physician.

Having thus described the invention, what is claimed and desired to be secured by Letters Patent is:

1. A syringe for treating the posterior urethra with a liquid medicament comprising a barrel, adapted to receive and retain a body of liquid, a compressible bulb mounted on and communicating with the barrel, and a second, independently compressible, bulb 45 mounted on and communicating with the first bulb, compression of the second bulb creating a sufficient vacuum to cause the desired amount of liquid to enter the barrel when the bulb is released or to expel the liquid charge from the barrel into the anterior urethra, and subsequent compression of the first bulb acting to force the expelled liquid into the posterior urethra.

2. A syringe for treating the posterior urethra with a liquid medicament comprising a barrel, adapted to receive and retain a body of liquid, a compressible bulb mounted on and communicating with the barrel,

and a second, smaller, independently compressible, bulb, communicating with the barrel, the capacity of the smaller bulb determining the amount of liquid that shall be drawn into and discharged from the barrel at each operation of the device, such charge being expelled from the barrel into the anterior urethra by compression of said smaller bulb, and being forced into the posterior urethra by subsequent compression of the larger bulb.

3. A syringe comprising a barrel having a discharge outlet at one end and having two superposed compressible air bulbs mounted on its opposite end for the purpose described.

4. A syringe for urethral injection comprising a transparent barrel, having a discharge outlet at one end, a compressible air bulb mounted on the barrel and communicating with the interior thereof, and a second, smaller, independently compressible air bulb mounted on and communicating with the first said bulb.

5. A syringe comprising a barrel adapted to receive and retain a body of liquid having a suitable outlet, an air bulb supported by the barrel and communicating with the interior thereof and adapted when compressed to force a charge of liquid from the barrel, and a second air bulb adapted to discharge through the barrel a volume of air larger than said liquid charge, for the purposes specified.

6. A syringe comprising a barrel having a suitable outlet, and two superposed compressible bulbs adapted to deliver air to said barrel, the bulb directly communicating with the barrel being larger and having its walls of greater thickness than the other bulb.

7. A syringe comprising a barrel having an outlet at one end, a compressible air bulb fitted within the other end of the barrel and communicating with the interior thereof, and a second, independently compressible, air bulb mounted on and communicating with the first said bulb.

8. A syringe comprising a barrel having a tapering end portion provided with an outlet, a compressible air bulb fitted within the other end of the barrel and communicating with the interior thereof, and a second, smaller, and independently compressible, air bulb mounted on and communicating with the first said bulb.

In testimony whereof I affix my signature.

MORRIS ABRAMOVITZ, M. D.
